CONVERTIBLE STUDIO BED

Walter P. Margulies, Forest Hills, N. Y., assignor
to Hotels Statler Company, Inc., New York,
N. Y., a corporation of New York

Application January 1, 1942, Serial No. 425,275

2 Claims.

(Cl. 5—59)

The invention relates to combination sofa beds. It is an object of my invention to provide an improved type of convertible sofa bed which is especially adapted for use in hotels and apartments, and which offers all of the advantages of regulation size beds in addition to providing a comfortable sofa.

Another object of my invention is to provide a bed having a full size one-piece mattress and a full size fixed-position spring in combination with means for converting the bed into a seat of sofa-depth with a comfortable back-rest.

A further object is to provide an article of furniture of the class described which is convertible from bed to sofa, or vice versa, without the necessity of rearranging bedding, and without moving the piece away from the wall.

A still further object is to provide, in combination with a full size single bed, a movable back-rest which is so constructed and arranged as to be movable into a position which reduces the area of the bed to that of a sofa, while at the same time providing a broad flat surface extending rearwardly of the back-rest in position to serve as a shelf.

Other objects and advantages of my invention will appear as the description proceeds.

In the drawings, wherein I have illustrated a preferred embodiment of the invention:

Fig. 1 is a perspective view of a sofa bed or studio bed as arranged for use as a sofa.

Figs. 2, 3 and 4 are vertical transverse cross-sectional views of this preferred embodiment of my invention, Fig. 2 showing the sofa arrangement, Fig. 3 the bed arrangement, and Fig. 4 an intermediate position of the sofa back-rest during the process of converting the sofa into a full size single bed.

Figs. 5 and 6 are plan views of the same embodiment arranged respectively as sofa and bed.

Figs. 7 and 8 are detail sectional views taken as indicated at 7—7 and 8—8 in Figs. 2 and 3, respectively.

One of the principal problems in providing a thoroughly satisfactory studio or sofa bed has been to achieve in a single article of furniture a sofa presenting a seat of normal depth or seating area which can be converted into a bed of full width or sleeping area. Falling short of this goal, many compromises have been made in devices heretofore proposed or used for the purpose stated. Some, in order to effect a transformation from a seat of sofa depth to a bed of adequate width, have resorted to complicated ar-

rangements in which the mattress and springs must be folded and unfolded in effecting the conversion, which arrangement is cumbersome to handle, and required separate storage of the bedding. Another compromise has been to make the bed a little narrower and the seat a little deeper, which results in a sofa which is uncomfortable, and in a bed of less than adequate width.

In accordance with my invention, a full width single bed can be quickly and easily converted into a sofa having a seat of normal depth (front to back) without disturbing the bed. With reference to the accompanying drawings, I shall now describe the manner in which this is accomplished. The studio bed which I have shown for purposes of illustration comprises in its general arrangement a frame 10 arranged to accommodate a box spring 11 and mattress 12, end boards 13, a longitudinally extending back-rest 14 pivotally mounted as at 15 to the end boards 13 by means of extended pivot arms 16 to swing about a substantially horizontal axis from a substantially vertical position behind the bed (Fig. 3) to an inverted position overlying a portion of the bed (Fig. 2).

The pivot axis is located forwardly of the longitudinal edge of the mattress as clearly shown, for example, in Fig. 2, and this arrangement of the pivot axis in conjunction with the projecting pivot members 16 brings the back-rest 14 into an operative position above the mattress at a substantial distance forwardly of the rearward longitudinal edge of the mattress, and in which all portions of the back-rest lie forwardly of a vertical plane which contains the rearward longitudinal edge of the mattress. On the other hand, when the back-rest is swung into the position shown in Fig. 3, all portions of the back-rest lie rearwardly of the rearward longitudinal edge of the mattress, freeing the full area of the bed for reclining use.

With particular reference to Figs. 5 and 6, it will be seen that by my invention it is possible to convert a full size single bed with a free useable width *a* (Fig. 6) into a sofa in which the seating area has been reduced to a normal depth *b* (Fig. 5)—i. e., a seat of "sofa-depth".

Another feature of my invention resides in the provision of a back-rest 14 and shelf member 17 hinged edge to edge as at 18, so that the back-rest and shelf, when in the position shown in Fig. 2, together cover that portion of the area of the bed which is not to be used for seating purposes. In addition, this arrangement provides a con-

venient broad shelf or table area behind the sofa on which ash trays, glasses, magazines or other articles may be placed.

The shelf 17 is provided with guide members 19 (Fig. 7) projecting from each end for engagement with a guide slot 20 which may conveniently be formed in the end boards 13. If desired, the members 19 may be provided with rollers 21 for engagement with the sides of the slots 20. These slots may, if desired, be lined with metal or other wear-resistant material.

It will be understood that the invention is applicable to various forms of frame constructions, so as to accommodate the desired type of spring and mattress. In the particular embodiment illustrated, I have shown a wood frame 10 having a heavy reinforced back member 22, front member 23 and the end boards 13 previously mentioned. Associated with the frame are means for supporting the mattress, such as the metal supporting elements 24 which are secured to the frame in any desired manner, and on which rests the base 25 of the spring 11. If desired, the bed may be provided with casters 26 holding the bottom of the frame somewhat above the floor. The guiding slot 20 formed in the end boards 13 extend in a generally vertical direction. From the lowermost point 27, the slots extend upwardly and preferably slightly toward the rear, as best seen in Fig. 2, to a point 28 approximately midway between the ends of the slot, thence upwardly and preferably slightly to the front to a point 29 (Fig. 4), thence forwardly and preferably slightly downwardly to the end point 30. Thus, in my preferred construction, the slot is bowed rearwardly, and is formed with a shoulder 31 at its upper end. The rearwardly bowed construction of the slots guides the shelf member 17 during the conversion from sofa to bed, or vice versa, in such a manner as to clear the rearward side of the mattress and bedding while at the same time keeping the edge 32 of the shelf member at all times forwardly of a vertical plane defined by the rearmost edge of the frame. The shoulder 31 serves to hold the back-rest and shelf steadily in the position shown in Fig. 2 when my article of furniture is made up as a sofa.

The pivotal mounting of the extended arms 16 of the back-rest to the end boards 13 preferably includes a mounting plate 33 which may be attached to the end boards in any convenient manner, as by means of screws. In the construction I have illustrated, this plate has a rearward extension 34 which may conveniently form a stop for cooperation with a flange 35 (Fig. 8) formed on each of the pivot arms 16 so that when the sofa is converted into a bed, as shown in Fig. 3, the flanges 35 of the pivot arms engage the rearward extensions 34 of the mounting plates 33 so that the weight of the back-rest and shelf are carried directly on the end boards. If desired, a stop may be provided for the back-rest to limit its movement in the opposite direction and support it when in the position shown in Fig. 2, although I prefer to permit the back-rest to rest directly on top of the bedding as shown. In this position it assists in holding the bedding in place at a point substantially forward of the rearward edge of the mattress, keeping the sofa smooth and neat.

The end boards 13 may be of any desired configuration as, for example, being cut away forwardly of the sofa position of the back-rest to provide arm rests 36.

It is believed that the operation of my inven-

tion will be clear from the foregoing description, but the manner of converting from sofa to bed and vice versa may be briefly summarized as follows:

Let us assume that my article of furniture is made up as a sofa, as shown in Fig. 2, with the bedding covering the mattress and tucked in all around to make a smooth surface for seating purposes. When it is desired to convert the sofa into a bed, it is necessary only to slide the fingers beneath the lower edge of the back-rest and lift up in the direction indicated by the arrow c in Fig. 4. This automatically slides the guide members 19 off the shoulders 31 of the guide slots in the end boards, whereupon the shelf is guided downwardly so that upon completion of the full arc of movement d, it reaches the position shown in Fig. 3 in which the shelf is suspended in a substantially vertical position close to the rearward edge of the mattress with the under side of the back rest also in a substantially vertical position in line with, or slightly to the rear of, a vertical plane containing the rearward longitudinal edge of the mattress. This frees the entire area of the bed for reclining use. Then all that is required is to turn down the bedding.

The back-rest may be of any desired construction with a wood or plywood back upholstered in any suitable manner, as by means of applying thereto a fabric over a sponge rubber cushion. My construction is adaptable to varying thicknesses of bed coverings, for the back-rest simply swings down against the top of the bed, and there is sufficient clearance at the forward end of the slots 20 above the shoulder 31 to take care of a certain amount of variation in the forward position of the back-rest.

In addition to the advantages heretofore enumerated, it will be observed that when the piece is made up as a bed, the smooth flat under surface of the back-rest forms a wainscot which protects the wall, keeping it clean, and also keeping the upholstered portion of the back-rest clean and free from spots. This is very important in hotels where frequent redecoration of walls is necessary when the bed is placed against, or near, a wall.

The angle of inclination of the back-rest 14 is subject to variations without altering the essential purposes, operation, or advantages of my invention, as are also other details of the construction illustrated. The terms and expressions which I have employed are used in a descriptive and not a limiting sense, and I have no intention of excluding such equivalents of the invention described, or of portions thereof, as fall within the purview of the claims.

I claim:

1. In an article of furniture of the class described, a frame arranged to accommodate a mattress, end boards, a longitudinally-extending back-rest fixedly pivoted to the end boards to swing about an axis located above the mattress, the pivot axis being a substantial distance from the plane of the back-rest, a shelf hinged to the back-rest, and guiding means including members connected to the shelf and slots fixed with respect to the end boards, said members having a slidable engagement with said slots and being arranged to bring the shelf into substantially horizontal position when the back-rest is in operative position and to bring the shelf into substantially vertical position below the back-rest when the back-rest is swung back into inverted position.

2. In a convertible studio bed including a supporting frame and a mattress carried upon said frame, a back-rest and shelf hinged edge-to-edge, the back-rest being pivotally mounted on the supporting frame to be swung from a position at the rear of the supporting frame into a position overlying the rear portion of the mattress, and the shelf being pivotally and slidably mounted on the

supporting frame to swing coordinately with said back rest from a substantially vertical position at the rear of the supporting frame into a horizontal position behind said back rest and overlying the rear portion of the mattress, the movement of the shelf being upwardly and thence forwardly from the back of the bed.

WALTER P. MARGULIES.
